UNITED STATES PATENT OFFICE

148,032

DESIGN FOR A STAPLING APPLIANCE

Charles M. Lindstrom, East Greenwich, R. I., assignor to Boston Wire Stitcher Company, Warwick, R. I., a corporation of Maine

Application June 26, 1946, Serial No. 131,061

Term of patent 14 years

(Cl. D74—1)

To all whom it may concern:

Be it known that I, Charles M. Lindstrom, a citizen of the United States, residing in East Greenwich, in the County of Kent and State of Rhode Island, have invented a new, original, and ornamental Design for Stapling Appliance, of which the following is a specification, reference being had to the accompanying drawings, forming a part thereof.

Fig. 1 is a side elevation of a stapling appliance showing my new design;

Fig. 2 is a top plan view thereof; and

Figs. 3 and 4 are elevational views of the head and handle ends thereof, respectively.

I claim:

The ornamental design for a stapling appliance, substantially as shown.

CHARLES M. LINDSTROM.
